REFRIGERATOR CABINET OR THE LIKE

William G. Rundell, Smyrna, Del., assignor to Clark
Equipment Company, a corporation of Michigan

Filed May 19, 1966, Ser. No. 2,349

Term of patent 14 years

(Cl. D67—3)

FIG. 2

FIG. 1

The dominant features of the design reside in the portion shown in full lines.

I claim:

The ornamental design for a refrigerator cabinet or the like, as shown and described.
